UNITED STATES PATENT OFFICE

2,145,833

INDIRECTLY HEATED CATHODE

George J. Imboden, Emporium, Pa., assignor to
Hygrade Sylvania Corporation, Salem, Mass.,
a corporation of Massachusetts

Application March 29, 1937, Serial No. 133,541

4 Claims. (Cl. 250—27.5)

This invention relates to electron discharge tubes and more particularly to such tubes as employ electron emitters of the indirectly heated or unipotential type.

5 A principal object of the invention is to provide an improved structure of indirectly heated cathode for radio tubes and the like.

A feature of the invention relates to an indirectly heated cathode which is specially shaped to prevent it slipping, turning or changing its 10 spacial relation with respect to the remaining electrodes of a tube mount.

Another feature relates to an indirectly heated cathode which is particularly well-suited for 15 use with a surrounding electrode such as a control grid or plate of flattened helical or tubular form.

A further feature relates to a specially shaped cathode sleeve for indirectly heated cathodes 20 having a connector tab fastened thereto in such a position as to avoid the necessity of employing a notched circular perforation in the usual mica or ceramic insulator spacer.

Other features and advantages not specifically 25 enumerated will be apparent after a consideration of the following detailed descriptions and the appended claims.

While the invention will be illustrated herein 30 as embodied in an electron discharge tube of the triode type, it will be understood that this is done merely for explanatory purposes and not by way of limitation. Accordingly in the drawing,

Fig. 1 is an elevational view, partly in section, 35 of a typical radio tube mount embodying the invention.

Fig. 2 is a top plan view of the mount of Fig. 1.

Fig. 3 is an enlarged view of part of Fig. 2. Fig. 3a is a detail view of part of the mica spacer of Figs. 1 and 3. Fig. 3b shows a modification 40 of Figs. 1 and 3.

Fig. 4 is an enlarged side view of the cathode shown in Fig. 1.

Fig. 5 is an enlarged front view of the cathode.

Fig. 6 represents a modification of the invention.

Referring to Fig. 1, the numeral 1 represents in dotted outline any well-known form of enclosing envelope such as customarily employed 50 in radio tubes and the like and while the drawing shows an envelope of the glass type, it will be understood that a metal envelope may be employed. Sealed into the envelope is any well-known form of radio tube mount comprising the 55 stem or base 2 wherein are sealed the various

lead-in and support wires 5 to 11 inclusive. Supported on the wires 5 and 11 is the anode 12, preferably, although not necessarily, in the form of a flattened tubular member of metal, graphite, carbon or the like. Supported on the wires 6 5 and 10 is the grid electrode 13 which may be of any well-known foraminous structure and merely for purposes of illustration it is shown in the drawing in the form of a fine helically wound wire supported on and attached to the grid side 10 rods 14, 15.

Coaxially disposed within both the grid and plate is an indirectly heated cathode according to the invention which cathode is indicated generally by the numeral 16. Supported within the 15 cathode and suitably insulated therefrom is any well-known form of heater wire the free ends of which are connected to the wires 7 and 9. For the purpose of making electrical connection to the emissive coating on the cathode there is 20 provided a metal tab 17 which is connected to the wire 8. In order to maintain the spacial positions of the various electrodes there are provided upper and lower insulator spacer members 18 and 19 respectively, these members being of 25 any suitable insulation material. Preferably, although not necessarily, members 18 and 19 are of mica sheets or discs having the necessary perforations to receive the ends of the various side rods and also the ends of the cathode, it being 30 understood that the mica discs are held in place on the wires 5 and 11 by metal tabs, eyelets or similar means fastened to the said wires.

In accordance with the invention the cathode comprises a metal sleeve of nickel or other similar 35 metal having a cylindrical portion 20 at its upper end and a similar cylindrical portion 21 at its lower end. The intervening part of the metal sleeve is flattened to provide a periphery having the same general shape as the shape of the grid 13 and of the plate 12 as shown more clearly in Fig. 2. The flattening of the major length of the sleeve results in the forming of upper and lower shoulders 22, 23 which are adapted to engage the mica members 18 and 19 respectively 40 so that the said sleeve is firmly held between the said mica members and is prevented from shifting vertically. Each of the mica members is provided with a circular perforation to accommodate the cylindrical ends of the sleeve. 50 As indicated in Fig. 4, the cathode tab 17 is disposed within the cylindrical portion 21 to which it may be welded, consequently both the upper and lower mica spacers may be perforated in an identical manner. Heretofore it has been the 55

usual practice to weld the tab 17 to the outer face of the cathode sleeve thus necessitating the provision of a circular perforation in the lower mica the edge of the perforation requiring a notch to accommodate the tab. This notching of the mica not only increased the cost of fabricating the mica but required two separate kinds of micas, namely those for the top of the mount and those for the bottom of the mount. The flattened part of the cathode is provided with an electron emissive coating 24 of known materials.

Preferably, although not necessarily, the perforation in the mica to receive the cathode, is provided with two diametrically disposed notches or slots 24a so that part of the flattened shoulder 22 may project therethrough as indicated in Fig. 3a, thus preventing the cathode sleeve from turning about its vertical axis. If desired, the slots 24 may be sufficiently long to permit the mica to pass beyond the shoulders 22. This latter arrangement while it prevents turning of the cathode sleeve does not permit the mica to prevent longitudinal movement of the sleeve.

The particular shape of the cathode as shown not only improves the electrical characteristics of the tube by having the emitting surface correspond to the shape of the grid 13, but it also reduces the cost of manufacture of the tube and also reduces the percent of rejects. This results from the fact that the assembly or threading of the sleeve into the mica spacers merely requires the insertion of the cylindrical ends, and the shoulders 22, 23 positively prevent the micas coming in contact with the emissive coating during the threading operation. Furthermore the shoulders 22, 23 positively space the micas from the end turns of the grid and serve as means for accurately spacing the mica members vertically apart.

Various changes and modifications may be made herein without departing from the spirit and scope of the invention. Thus instead of flattening the main length of the cathode sleeve, this sleeve may be retained in its cylindrical form and the end or end portions flattened to provide the spacing shoulders. Such an arrangement is indicated in Fig. 6 wherein the upper end 25 of the cathode sleeve is flattened while the main body 26 of the sleeve is in its usual cylindrical form. The mica member 27 is provided with a slot 28 conforming to the flattened portion 25

and through which slot the said end protrudes. The mica 27 therefore engages the shoulder 29 on the cathode sleeve to prevent vertical movement of the cathode, and the flattened end 25 prevents turning movement of the cathode. It will be understood of course that the flattened portions 25 of the cathode sleeve may be provided at either or both ends.

What I claim is:

1. A radio tube mount comprising an indirectly heated cathode, a surrounding electrode for said cathode, said electrode having at least one side rod projecting beyond the ends thereof, a pair of insulator spacer members having aligned openings to receive the ends of said cathode and said side rod, said cathode having cylindrical end portions joined to a flattened tubular portion the juncture of cylindrical portions and the tubular portion defining shoulders, and means for fastening said spacer members on said side-rod so that they abut against said shoulders at opposite ends of the cathode, at least one of said spacers having a circular opening to receive a cylindrical end of the cathode, said opening also having lateral notches to receive part of the flattened tubular portion of the cathode to restrain the cathode against turning movement.

2. A radio tube mount according to claim 1 in which a connector tab is fastened to the inner face of the lower cylindrical end portion of the cathode, and both said spacer members are provided with the same shape perforations.

3. A radio tube mount including an indirectly heated cathode having the major part of its length formed to a flattened tubular shape and terminating in at least one cylindrical end, a coating of electron-emissive material on said flattened portion, and a mica spacer disc having a perforation with a circular portion and two oppositely disposed notches, said disc being assembled over the cathode so that the cylindrical end of the cathode passes through said circular portion and at least part of said flattened section of the cathode registers with said notches to restrain said cathode against turning movement with respect to the disc.

4. A mount according to claim 3 in which a metal tab is fastened to the inner face of said cylindrical end of the cathode so as to lie entirely within the circumference of said end.

GEORGE J. IMBODEN.
